TAPE DECK

George Adams and John Hawkins, New York, N.Y.,
assignors to United Research Laboratory, New York,
N.Y.

Filed May 18, 1970, Ser. No. 23,051

Term of patent 14 years

Int. Cl. D14—01

U.S. Cl. D26—14

FIG. 1

FIG. 2

FIG. 3

FIG. 4

FIG. 5

FIG. 1 is a top plan view of a tape deck embodying our new design;

FIG. 2 is a front elevational view of the tape deck of FIG. 1;

FIG. 3 is a side elevational view from the left of said tape deck;

FIG. 4 is a rear elevational view of the tape deck; and

FIG. 5 is a side elevational view from the right of the tape deck.

We claim:

The ornamental design for a tape deck, substantially as shown.
